(57) CLAIM

The ornamental design for an exercise apparatus, as shown and described.

DESCRIPTION

FIG. 1 is a top perspective view of an exercise apparatus, showing my new design;

FIG. 2 is a front elevation view thereof, the rear elevation view being a mirror image thereof;

FIG. 3 is a left-side elevation view thereof;

FIG. 4 is a right-side elevation view thereof; and,

FIG. 5 is a top plan view thereof.

The bottom view not shown forms no part of the claimed design.
